(57) **CLAIM**

The ornamental design for a wildlife guard for discharge brackets, as shown and described.

DESCRIPTION

FIG. 1 is a perspective view;

FIG. 2 is a front view;

FIG. 3 is a rear view;

FIG. 4 is a right side view;

FIG. 5 is a left side view;

FIG. 6 is a bottom view; and,

FIG. 7 is a top view.

The broken lines depict portions of the wildlife guard for discharge brackets that form no part of the claimed design.
